(57) **CLAIM**

We claim the ornamental design for portions of a latch assembly, as shown and described.

DESCRIPTION

FIG. 1 is a perspective view showing front, left and first end features of one form of portions of a latch assembly showing our new design;

FIG. 2 is a front view thereof;

FIG. 3 is a left side view thereof, it being understood that a right side view is identical hereto but a mirror image reversal hereof;

FIG. 4 is a first end view thereof;

FIG. 5 is an opposite end view thereof;

FIG. 6 is a rear view thereof;

FIG. 7 is a perspective view showing front, left and first end features of another form of our new design;

FIG. 8 is a front view thereof;

FIG. 9 is a left side view thereof, it being understood that a right side view is identical hereto but a mirror image reversal hereof;

FIG. 10 is a first end view thereof;

FIG. 11 is an opposite end view thereof; and,

FIG. 12 is a rear view thereof.

The broken line disclosure in the drawings is provided for illustrative purposes only and forms no part of the claimed design.
